PROCESS FOR CONVERTING NORMALLY
GASEOUS HYDROCARBONS INTO MOTOR
FUELFrederick E. Frey, Bartlesville, Okla., assignor to
Phillips Petroleum Company, a corporation of
Delaware

Application March 24, 1936, Serial No. 70,656

6 Claims. (Cl. 196—10)

This invention relates to the conversion of normally gaseous hydrocarbons into motor fuel, and more specifically this invention relates to the production of increased yields of hydrocarbons suitable for motor fuels boiling in the gasoline range with decreased production of polymeric products of higher boiling point.

Normally gaseous paraffins or olefins are converted into normally liquid hydrocarbons of the type of gasoline by the application of pressure and heat at a temperature level sufficient to effect reaction whereby the polymerization of olefin hydrocarbons into hydrocarbons of high molecular weight is effected, and also the conversion of paraffin hydrocarbons provided the temperature level is sufficiently high to effect their decomposition into olefins which subsequently polymerize. The polymerization reaction in the initial stages effects the formation of volatile normally liquid hydrocarbons, but as reaction proceeds hydrocarbons of increasingly higher weight are built up, part of which are relatively heavy and have a boiling range above that of gasoline when the reaction is sufficiently protracted to effect the conversion of a large fraction of the original hydrocarbon into polymeric products. In comparison with gasoline, the heavier hydrocarbon polymers are of comparatively little value and the production of a maximum yield of the more volatile products and the minimum amount of the heavier products is accordingly desirable. It has been proposed to reduce the quantity of heavier polymers formed in such an operation by returning the heavier polymers to the reaction zone wherein a cracking or depolymerizing is effected, and more or less of the heavier polymers are converted into products boiling within the gasoline range. When such a thermal treatment is applied to gaseous hydrocarbons which are largely paraffinic, elevated temperature and reaction time sufficient to effect splitting reactions are required, and under such conditions I have found that the heavier polymers are largely aromatic in character. When such hydrocarbons are returned to the reaction zone a limited amount of gasoline is produced from the aliphatic structures present. At the same time aromatic and unsaturated hydrocarbons, comparatively resistant to decomposition by heat, unite with lighter hydrocarbon molecules to produce heavy products of essentially aromatic structure. I have found further, however, that the conversion of gases of high olefin content, if conducted at sufficiently high pressure, can be effected at comparatively low reaction temperatures to produce

gasoline hydrocarbons and at the same time produce heavier polymers of markedly different characteristics which are largely aliphatic. Such a heavier polymer will decompose largely into gasoline and lighter hydrocarbons at a pyrolysis temperature, and can be returned to the reaction zone wherein partial decomposition into gasoline and lighter hydrocarbons will take place. At the same time the formation of additional amounts of aromatic heavy products takes place by union with lighter unsaturated hydrocarbons present to produce an increased amount of heavy aromatic products. Because of the mild reaction temperature and high partial pressure of lower unsaturated hydrocarbons the undesirable latter reaction takes place to a considerable degree.

The object of this invention is to provide a novel method for effecting more efficient conversion of heavier polymers from the last mentioned type of polymerizing operation, into hydrocarbons boiling within the gasoline range by subjecting them in a second reaction step, and in the presence of gaseous hydrocarbons undergoing thermal conversion, to conditions of higher temperature and lower pressure whereby a maximum production of gasoline hydrocarbons is obtained with a lessened formation of additional heavy aromatic polymers.

The process will be understood from the following description: Hydrocarbons suitable for the process are those gaseous hydrocarbons which undergo conversion under comparatively mild conditions and preferably a conversion stock consisting largely of olefins is used for this process.

With reference now to the drawing, which constitutes a part of this specification, the figure illustrates diagrammatically one form of apparatus for effecting the present process for converting normally gaseous hydrocarbons into motor fuel.

The conversion stock which may consist of normally gaseous hydrocarbons of predominantly three and four carbon atoms per molecule, and which may have been derived from cracking still gases is drawn through a conduit or pipe 10 by the pump 11, and is forced into a reaction zone or heated tube coil 12 maintained under a pressure of at least 500 pounds per square inch and at a temperature preferably below 1000° F. Coil 12 may be heated in any desired manner in the furnace 13, and polymeric products are formed in the coil 12 as the result of such temperature and pressure treatment of the conversion stock. The thermally treated hydrocarbons pass from the coil 12 through pipe 14 to a series of fractionators

which are diagrammatically illustrated by the fractionator 15 and wherein there is separated a fraction composed of normally gaseous hydrocarbons, a fraction which is essentially gasoline, a heavy fraction composed of hydrocarbons of a higher boiling point than gasoline, and a fourth fraction of relatively small volume which consists of heavy tar of a still higher molecular weight.

The first mentioned fraction consisting of normally gaseous hydrocarbons surviving thermal treatment in the reaction coil or zone 12 and depleted of the more readily converted components passes through conduit 16 to a second reaction zone or heated coil 17, which is contained in a suitable furnace 18, and wherein more drastic conditions of thermal treatment are maintained than in reaction coil or zone 12 and wherein there may exist a higher pressure by virtue of pump 19. If it is not desired to maintain a high pressure in reaction zone or coils 17 the hydrocarbon materials flowing thereto may be bypassed from pipe 16 through pipe 20 controlled by the valve 21. The temperature in reaction coil 17 is usually 1,000° F. or higher and the pressure 3,000 pounds or lower.

The second or gasoline fraction from the fractionator 15 is discharged from the system through pipe 22.

The third fraction above mentioned separated in fractionator 15 namely the polymers heavier than gasoline, flow therefrom through pipe 23 and are introduced wholly or in part into the reaction coil 17 by way of pipe 24 controlled by the valve 25 and which makes connection with pipe 16, or this third fraction consisting of polymers heavier than gasoline may be caused to flow from pipe 23 through pipe 26, controlled by the valve 27, and enter the reaction coil 17 at an intermediate point thereof within the furnace 18 as illustrated in the drawing. This latter mode of introducing the third fraction consisting of polymers heavier than gasoline is resorted to when a shorter reaction period produces better results, or is otherwise desired.

The fourth fraction consisting of the heaviest products from the reaction coil 12 need not be removed from the system in some cases, but may be introduced through pipe 28 to the pipe 23 by flowing it through pipe 29 controlled by the valve 30 and thence to the reaction coil 17 by way of pipe 16, or it may be withdrawn from the system by the pipe 31 controlled by the valve 32.

In reaction coil 17 a conversion of the charge into normally liquid hydrocarbons takes place, the major part being contributed by the incoming gaseous hydrocarbons and a smaller part by the decomposition of the heavier hydrocarbons introduced. The thermally treated material passes from the reaction coil 17 by way of pipe 33 to a series of fractionators which are also diagrammatically illustrated by the fractionator 34 wherein light gaseous hydrocarbons are separated from the mixture and may be discarded through the pipe 35. In fractionator 34 gasoline and heavier hydrocarbons are separated and discharged through pipe 36, and the normally gaseous hydrocarbons suitable for retreatment are separated from the mixture and may be returned through pipe 37 to pipe 16 for retreatment in the reaction coil 17.

Suitable fractions consisting of the more reactive gaseous hydrocarbons, and preferably high in olefin content, may be returned from the fractionator 34 through pipe 38 by means of the

pump 46 and introduced into pipe 10 whereby they are caused to enter the reaction coil 12 along with the other gaseous hydrocarbons being treated in this process.

An additional fraction, consisting of the more reactive gaseous hydrocarbons and preferably high in olefin content, may be withdrawn from the series of fractionators illustrated diagrammatically by the fractionator 15, through pipe 39 controlled by the valve 40 and passed through pipe 41 by means of pump 42 to feed the same into pipe 10 along with the charge therein.

In some instances it may be desirable to withdraw a portion of the material flowing through pipe 16, namely the first fraction, and introduce it into pipe 10 along with the charge therein, and when this is desired valve 43 in pipe 44 is opened thus allowing a part of the material in pipe 16 to flow through pipes 44 and 41 and into pipe 10.

Gaseous hydrocarbons may also be introduced from an outside source to the reaction coils 17, and to effect this pipe 45 is provided which connects with pipe 16 leading to the coil 17.

Hydrocarbons most suitable for conversion in the first thermal treatment effected in coil 12 contain preferably over 20 per cent olefins and may be gases derived from oil cracking or from hydrocarbon gas pyrolysis. The conversion conditions required to effect conversion of gaseous olefins by heat and pressure are well known and will be in the neighborhood of 750° to 1,000° F. at pressures of 500 to 3,000 pounds per square inch and higher, the higher pressures being desirable when olefin content is not high with a reaction in the range .5 to 3 minutes, the time being dependent upon the temperature and pressure level employed. A conversion into polymeric products equivalent to 40 per cent or more of the olefin present is usually desirable for economic conversion and the polymeric products will contain from 15 to 35 per cent of hydrocarbons boiling above the gasoline range, which usually embraces temperatures up to about 400° F. With the thermal treatment conducted under substantially the conditions described the gasoline will contain only a minor proportion of aromatics. The second conversion step conducted in reaction coil 17 will normally be conducted under more drastic conditions such that gaseous paraffin hydrocarbons, ethane, propane and butane, will be substantially decomposed while concurrent polymerization of the gaseous olefins takes place and requires, for the efficient conversion of the heavier polymer introduced, a higher temperature and in any case a more drastic time-temperature condition than does the first reaction step of coil 12. In this operation temperatures of about 1,000° to 1,400° F. are required and operating pressures of from 3,000 pounds per square inch more or less to about 200 pounds per square inch, the lower temperatures within the range being used with the higher pressures. Operation under the conditions described leads to the formation of heavier polymers accompanying the gasoline produced which are of high specific gravity and mostly aromatic.

For treatment in this process gaseous hydrocarbons varying in composition over a wide range may be used. All gaseous hydrocarbons are convertible except methane which is substantially inert under these conditions. Conversion under mild conditions, in coil 12 (step 1) requires that 20 per cent or more of olefins be present and preferably 35 per cent or more. Lower olefin contents are converted more satisfactorily if butanes, which are the only paraffin hydrocarbons react-

ing extensively under mild conditions, are present to the extent of 40 per cent or more. By the expression "gaseous hydrocarbons containing a substantial proportion of reactive components" is meant hydrocarbons of the composition above defined.

I claim as my invention:

1. A process for converting a normally gaseous hydrocarbon mixture containing both unsaturated and saturated components into normally liquid hydrocarbons of the motor fuel boiling range, which comprises thermally treating such a mixture under a pressure greater than 500 pounds per square inch at a temperature between 750° and 1,000° F. in a first reaction zone and producing normally liquid hydrocarbons, separating from the effluents of said first reaction zone a first fraction consisting of normally gaseous hydrocarbons, a second fraction consisting of normally liquid hydrocarbons boiling in the motor fuel range and a third fraction boiling above the motor fuel range, and thermally treating said first fraction in admixture with said third fraction and in the absence of hydrocarbon oils from an extraneous source in a second reaction zone under a pressure between 200 and 3,000 pounds per square inch at a temperature between 1,000° and 1,400° F. and such that aromatic hydrocarbons are produced in said second reaction zone.
  2. In a process for converting a mixture of normally gaseous hydrocarbons containing a substantial proportion of reactive components into normally liquid hydrocarbons suitable for motor fuel, the steps which comprise thermally treating a mixture of gaseous hydrocarbons containing a substantial proportion of reactive components under a pressure between 500 and 3,000 pounds per square inch and within the temperature range of 750° to 1,000° F. to produce normally liquid hydrocarbons, separating from the resultant mixture a first fraction consisting of normally gaseous hydrocarbons and a second fraction consisting of normally liquid hydrocarbons boiling in the gasoline range and a third fraction consisting of hydrocarbons boiling above the gasoline range, thermally treating said first fraction in admixture with said third fraction and in the absence of hydrocarbon oils from an extraneous source under a pressure between 200 and 3,000 pounds per square inch within the temperature range of 1,000° to 1,400° F. and such that aromatic hydrocarbons are produced in said second reaction zone, separating from said thermally treated fractions said normally liquid hydrocarbons and removing them from the process, and also separating a mixture of gaseous hydrocarbons containing a substantial proportion of reactive components and admixing the same as a part of the first mentioned mixture of gaseous hydrocarbons containing a substantial proportion of reactive components.
  3. A process for converting a normally gaseous hydrocarbon mixture containing a substantial proportion of reactive components into normally liquid hydrocarbons of the boiling range of gasoline, which comprises passing such a hydrocarbon mixture while under a pressure between 500 and 3,000 pounds per square inch and at a temperature of 750° to 1000° F. through a first reaction zone wherein normally liquid hydrocarbons are formed, separating from the thermally treated hydrocarbon mixture a first fraction consisting of normally gaseous hydrocarbons, a second fraction consisting of normally liquid hydrocarbons in the gasoline boiling range and
- removing it from the process, and a third fraction containing hydrocarbons boiling above the gasoline boiling range, passing said first fraction together with said third fraction and in the absence of hydrocarbon oils from an extraneous source to a second reaction zone wherein the last mentioned fractions are mingled and subjected to a conversion temperature of 1000° to 1400° F. while under a pressure greater than 200 pounds per square inch and less than that in said first conversion zone and such that aromatic hydrocarbons are produced in said second reaction zone, whereby an optimum conversion to gasoline boiling range hydrocarbons takes place, and then separating from the hydrocarbons thermally treated in the second reaction zone the normally liquid hydrocarbons produced therein.
4. A process for converting normally gaseous hydrocarbons into normally liquid hydrocarbons in the gasoline boiling range which comprises treating a normally gaseous hydrocarbon mixture substantially free of methane and containing at least 20 per cent of olefin hydrocarbons under a pressure between 500 and 3000 pounds per square inch in a first reaction zone maintained at a temperature between 750° to 1000° F. whereby normally liquid hydrocarbons are produced, separating from the effluents of said first reaction zone a first fraction consisting of normally gaseous hydrocarbons, a second fraction consisting of normally liquid hydrocarbons boiling in the gasoline boiling range and removing it from the process, and a third fraction consisting of normally liquid hydrocarbons boiling above the gasoline boiling range, treating said first fraction and said third fraction in the absence of hydrocarbon oils from an extraneous source under a pressure lower than that in said first reaction zone and between 200 and 3000 pounds per square inch in a second reaction zone maintained at a temperature between 1000° and 1400° F. and such that aromatic hydrocarbons are produced in said second reaction zone whereby an optimum yield of normally liquid hydrocarbons in the gasoline boiling range is produced, and separating from the effluents of said second reaction zone the gasoline boiling range hydrocarbons so produced.
5. A process for converting normally gaseous hydrocarbons into a maximum quantity of normally liquid hydrocarbons in the gasoline boiling range which comprises treating a normally gaseous hydrocarbon mixture substantially free of methane and containing at least 40 per cent of butanes and at least 20 per cent of olefin hydrocarbons under a pressure between 500 and 3000 pounds per square inch in a first reaction zone maintained at a temperature between 750° and 1000° F. whereby normally liquid hydrocarbons are produced, separating from the effluents of said first reaction zone a first fraction consisting of normally gaseous hydrocarbons, a second fraction consisting of normally liquid hydrocarbons boiling in the gasoline boiling range and removing it from the process, and a third fraction consisting of normally liquid hydrocarbons boiling above the gasoline boiling range, treating said first fraction and said third fraction in the absence of hydrocarbon oils from an extraneous source under a pressure lower than that in said first reaction zone and between 200 and 3000 pounds per square inch in a second reaction zone maintained at a temperature between 1000° and 1400° F. and such that aromatic hydrocarbons are produced in said second reaction zone where-

by an optimum yield of normally liquid hydrocarbons in the gasoline boiling range is produced, and separating from the effluents of said second reaction zone the gasoline boiling range hydrocarbons so produced.

6. A process for converting a normally gaseous hydrocarbon mixture containing both saturated and unsaturated hydrocarbons into normally liquid hydrocarbons of the gasoline boiling range, which comprises subjecting said mixture in a first zone to conditions of temperature and pressure sufficient to convert a substantial proportion of the unsaturated hydrocarbons to normally liquid products, separating from the

effluent of said zone a normally gaseous fraction, a fraction boiling within the gasoline range and a fraction boiling above the gasoline range, subjecting the first and last mentioned fraction in the absence of hydrocarbon oils from an extraneous source in a second zone to a higher temperature than said first zone and elevated pressure, said temperature and pressure being so regulated that a substantial proportion of aromatic products boiling within the gasoline range are produced, and separating the normally liquid hydrocarbons from the effluent of said second zone.

FREDERICK E. FREY.
